UNITED STATES PATENT OFFICE.

JAMES EDWARD MACK, OF HICKSVILLE, NEW YORK.

MECHANICAL INDEXING MEANS.

1,410,941.

Specification of Letters Patent. Patented Mar. 28, 1922.

Application filed March 21, 1921. Serial No. 454,234.

To all whom it may concern:

Be it known that I, JAMES EDWARD MACK, a citizen of the United States, and a resident of Hicksville, in the county of Nassau and 5 State of New York, have invented certain new and useful Improvements in Mechanical Indexing Means, of which the following is a specification.

My present invention relates to indexing 10 and proposes a readily expandible indexing system in lieu of the usual surname index which will promote decided advantages thereover, which will avoid the known disadvantages thereof, and which will be simple, readily understandable and definitely effective.

In the ordinary indexing by surname great difficulty is encountered unless the index outline is carried out to an annoyingly 20 great extent, it being impossible for instance to distinguish in an index carried out four place, between such names as,

Rose	Rosemont	Rosenfeld
Rosen	Rosenwald	Rosenbaum
Rosendall	Rosencrans	Rosengarten
Rosenberger	Roselle	

all of which would be indexed "Rose."

I propose means forming an index system where by the use of not over four outlines, these several names along with several others can be readily distinguished.

In the accompanying drawing,

Figure 1 is a plan view of a card showing 35 the indexing means applied to one name, and

Figures 2 to 6 inclusive are similar views showing the means applied to other names.

In carrying out my invention the first and 40 outstanding feature is the determination of the index word outline from the consonants of the word to be indexed for when it is considered that approximately nine of ten names have a vowel as either their first or 45 second letter and this vowel is either a, e or o, it is quite obvious that the index range when the vowels are utilized, is limited, while if the vowels are omitted, the range is materially widened and the chances of 50 duplication materially lessened. For instance take the names Sabin, Sacks, Sadler, Samuels, Sanborn, Sargent, Saxon indexed to two places utilizing the vowels, gives "Sa" in each instance while by utilizing the

consonants we get sb, sc, sd, sm, sn, sr, sx 55 respectively.

The next and not less important feature of my present system is the application of numerical indicators according to the relative frequency with which the letters designated by the numeral appear in ordinary construction, in order that in the final analysis ten combinations may be found which will work harmoniously and successfully, each combination or class having a separate 60 digit or numeric denominator. When we consider that in the average index about one name out of every nine begins with "S" and only about one in every three hundred begins with "Z," it becomes obvious that "Z" 65 can be classified with "S" and given the same numeric denominator with little danger of interference.

Bearing in mind therefore that the consonant outline of the object word is the index outline and that the digit denominators limited to ten in all for the various consonants and applied thereto in accordance with their relative frequency in ordinary construction, I have arbitrarily separated the 80 consonants into two classes called absolute and qualified, the latter consisting of the letters G—T—R—N.

Thus the absolute consonants may be divided and applied to digit denominators as 85 follows:

1.	2.	3.	4.	5.	6.	7.	8.	9.
C	B	L	S	J	H	M	F	P
K	D						V	W
							X	Y
							Z	Q

and examples thereof include the following:

Coe	1	Day	2	95
Cody	12	Daley	23	
Poe	9	Empey	79	
Padula	923	Leahy	36	

The qualified consonants G, T, R, and N are utilized when occurring initially but are 10 disregarded otherwise except when they are needed to bring the index outline to the necessary number of places. They are given the digit denominators

3	4	6	8
G	T	R	N

and for example would be disregarded in

carrying the indexing of the following words to three places—

5   *Harwood* 692 *Codman* 127
      Imperial 793 *Barbiers* 224
              (See Figure 1)

although if carried four places the index outline would be—

10   *Harwood* 6692 *Codman* 1278
      Imperial 7963 *Barbiers* 2624
              (See Figure 2)

In this index system it is proposed to treat double letters as one, including "CK" which is considered "KK," and it is also proposed that whenever "H" or "L" appears with another consonant without the interposition of a vowel, they shall be treated as compound. If the letter associated with either "H" or "L" is an absolute consonant, the compound is designated "5," but if the associated letter is a qualified consonant the compound is designated by "O." Thus,

25   *Shafer* 586 *Thaw* 09
      Slavin 588 *Hathaway* 609
      Chapin 598
              (See Figure 3)

Furthermore two qualified consonants ap-

pearing together without the interposition 30 of a vowel are treated as a compound and the compound designated as "O," for instance *Brenton*—2608. (See Figure 4.)

It becomes quite obvious therefore that the index outline may be carried out as many 35 places as desired or necessary and that this flexibility may be carried even further by including the Christian name in a name index, (see Figure 5), or for instance the address (see Figure 6). On the other hand 40 geographical or descriptive names may be contracted to prevent excessive duplication of index numbers.

I claim:

1. An indexing element having digits representing the consonant outline of indexed matter and corresponding to the letters of such outline in groups of letters according to the relative frequency of the occurrence 45 of such letters in average word construction.

2. An indexing element having digits representing certain letters of indexed words and corresponding to the letters in groups according to the relative frequency of such letters in average word construction, each 50 group having an indexing digit.

JAMES EDWARD MACK.
